UNITED STATES PATENT OFFICE.

JOSEPH BOIVIN, OF PATERSON, NEW JERSEY.

MACHINE FOR DRYING, LUSTERING, AND STRETCHING.

SPECIFICATION forming part of Letters Patent No. 739,253, dated September 15, 1903.

Application filed October 3, 1902, Serial No. 125,749. (No model.)

To all whom it may concern:

Be it known that I, JOSEPH BOIVIN, a citizen of the United States, residing in Paterson, in the county of Passaic and State of New Jersey, have invented certain new and useful Improvements in Drying, Lustering, and Stretching Machines; and I do hereby declare the following to be a full, clear, and exact description of the invention, such as will enable others skilled in the art to which it appertains to make and use the same, reference being had to the accompanying drawings, and to letters and figures of reference marked thereon, which form a part of this specification.

This invention relates to the treatment of silk in skeins subsequently to the operation of dyeing, so as to impart luster to the silk. After the skeins have been taken from the dye-bath and freed of the greater portion of their moisture by a hydro-extractor or some other suitable means they are, according to one common and well-known method of treatment, stretched while still damp from the dye-bath and while maintained stretched are subjected to the drying effects of a sufficiently-heated atmosphere. By thus stretching the skeins while still wet from the dye-bath and drying them while maintained stretched the silk is given a luster which is both perfect and permanent.

My invention consists in an improved apparatus for use in connection with the above-mentioned process in stretching the skeins and maintaining them stretched during the drying step of said process.

My invention further consists in providing such an apparatus with automatic means whereby when a predetermined tension has been placed on the skeins the stretching action of the apparatus will be caused to cease.

In the accompanying drawings, wherein my invention is fully illustrated, Figure 1 is a view in front elevation of my improved apparatus. Fig. 2 is a vertical sectional view on the line $\alpha\alpha$ in Fig. 1, and Figs. 3, 4, and 5 illustrate details.

a designates parallel beams forming, with transverse blocks b , which rest upon them, a base for certain parts of the apparatus, while c indicates an upright which, with a corresponding part d , which may be another and similar upright or a wall of the building in

which the apparatus is located, supports horizontal beams e and f , disposed the one above the other.

In bearings g , supported on the blocks b , are stepped vertical screws h , said screws being journaled near their upper ends in bearing-blocks i , bolted to the beam e . Each screw carries a series of pairs of cross-arms j and k , which it is the function of said screw to separate or bring together. The middle portion of each cross-arm has bolted to it a strap l , which, with the opposed portion of the cross-arm, is formed to fit the screw, Fig. 4. In the case of the cross-arm k the bore m thus formed in it for the reception of the screw is threaded, so as to engage the threading of the screw, while in the case of the cross-arm j said bore m is smooth.

n is a collar adapted to be adjustably fixed on the screw by a set-screw o between the two cross-arms in each pair and which acts as a stop for the cross-arm j . In view of the foregoing it will be seen that if the cross-arms are prevented from turning the rotating of the screw will cause the cross-arm k to move away from or approach the other cross-arm in each pair, according to the direction in which the screw is turned. The tendency of the cross-arms to turn with the screw is prevented by a vertical rod p , which is preferably secured in the beams e and f and the corresponding block g and which is held in place in a vertical recess q in each cross-arm by its strap l .

The cross-arms j and k are grooved longitudinally in their outer edges, and in these grooves are adapted to seat rods r . These rods are preferably made of wood and serve to keep the skeins (marked s) out of contact with the cross-arms, which for the sake of strength are preferably made of metal. As the rods r might become soiled by rust from the metallic cross-arms and damage the silk, I prefer to form these cross-arms, as shown at t in Fig. 5, with the portions thereof in which the rods directly seat composed of some non-oxidizable material, such as wood.

u is a horizontal shaft which is journaled in the support d and in a bearing-bracket v , sustained by the beam e . This shaft is adapted to be rotated by a crank w , which is preferably connected with the shaft by a sprocket-and-chain arrangement x . The shaft u car-

ries a series of bevel-gears y , which intermesh with other bevel-gears z , each surmounting one of the screws h . The upper end of each screw is reduced, as at 1, and receives a collar 2, which forms a bearing for the gear z , said gear being recessed, as at 3, for the reception of said collar. To keep the gear down on the collar, a cotter-pin 4 and washer 5 may be provided. (See Fig. 3.) The gear z is thus free to turn on the screw. On each screw below the corresponding gear z is keyed a clutch 6, which is formed with an annular groove 7, receiving a fork 8, which is fulcrumed on a bracket 9 on the beam e . Said clutch and the gear z are formed with interlocking ratchet-teeth 10 on their adjacent faces, so that when the clutch is forced against the gear the rotary movement of the former will be imparted to the latter, and consequently to the screw. Each fork 8 is connected with the beam f by levers 11, which are connected at 12, so as to form a toggle-joint. A stop 13 on one of them engages the other, so as to keep them end to end and alined; but if the joint is pushed against from the opposite side said levers will buckle, and thus draw the fork 8 downwardly. In order to actuate the levers, the cross-arm k in one of the pairs of cross-arms on the screw is provided with a lug 14, which as it moves downwardly with the cross-arm is adapted to engage said levers at their joint. It of course depends upon the form of the lug 14 as to just when in the downward movement of the cross-arm which carries it the levers will be actuated by said lug. By the mechanism above described when the stretching operation has proceeded to a predetermined extent it will be automatically stopped, the skeins being left to stand stretched at the degree of tension at which the increasing of the tension was stopped.

I do not wish to be limited to that embodiment of my invention herein particularly described and shown; but

What I do claim as new, and desire to secure by Letters Patent, is—

1. The combination of substantially parallel members adapted to receive the skeins to be operated upon and one of which is movable to and from the other, and a rotary part

formed with an inclined surface whereby said movable member is controlled, substantially as described.

2. The combination of substantially parallel members adapted to receive the skeins to be operated upon and one of which is movable to and from the other, a screw penetrating said members and engaging with its threaded portion the movable member, and a collar disposed between said members and forming a stop for the other member, substantially as described.

3. The combination of substantially parallel members adapted to receive the skeins to be operated upon and one of which is movable to and from the other, a screw penetrating said members and engaging with its threaded portion the movable member, a collar disposed between said members and forming a stop for the other member, and means for securing said members against rotation with the screw, substantially as described.

4. The combination of a pair of members for receiving the skeins to be operated upon, one of said members being movable to and from the other, means for moving said movable member away from the other member, disconective connecting mechanism between said movable member and its actuating means, and means for automatically actuating said disconective connecting means so as to disconnect said movable member from its actuating means, substantially as described.

5. The combination of a pair of members for receiving the skeins to be operated upon, one of said members being movable to and from the other, means for moving said movable member away from the other member, disconective connecting means between said movable member and its actuating means, and means, controlled by said movable member, for actuating said disconective connecting means, substantially as described.

In testimony that I claim the foregoing I have hereunto set my hand this 30th day of September, 1902.

JOSEPH BOIVIN.
